UNITED STATES PATENT OFFICE.

BUDD D. GRAY, OF GREENWICH, CONNECTICUT, ASSIGNOR TO AMERICAN THERMOPHONE COMPANY, OF BOSTON, MASSACHUSETTS, A CORPORATION OF MASSACHUSETTS.

THERMOPHONE.

1,398,687.

Specification of Letters Patent. Patented Nov. 29, 1921.

Application filed February 19, 1920. Serial No. 359,948.

To all whom it may concern:

Be it known that I, BUDD D. GRAY, of Greenwich, in the county of Fairfield and State of Connecticut, a citizen of the United States, have invented a new and useful Improvement in Thermophones, of which the following is a specification.

Because chiefly of its small size and the minuteness of its thermic elements the design and manufacture of a thermophone which will give satisfactory results in practical use and will be easy and economical to make and easy to repair, have not been simple.

My invention relates to a thermophone construction designed especially for use as a receiver, which gives an opportunity for a large number of thermic elements arranged in close proximity to each other in a small symmetrical chamber so as to secure sensitiveness and strength without increasing the size of the instrument. By my construction a larger number of hot wires may be used than is customary and they are arranged about a chamber of a character particularly well shaped for the originating and expelling of vocal sounds.

My invention will be understood by means of the drawings in which it is shown in its preferred form.

Figure 1 is a longitudinal section of a thermophone embodying my invention,

Fig. 2 being a cross section on line 2—2 of Fig. 1.

Fig. 3 is a side elevation.

Fig. 4 is a section of one of the segments from which the thermophone is made up.

Fig. 5 is a similar section showing the elements which it carries in elevation.

Fig. 6 is a side elevation of one of the elements, and

Fig. 7 a section on line 7—7 of Fig. 6.

The thermophone as shown in Figs. 1, 2 and 3 is drawn on an enlarged scale, and the device as shown in Figs. 4, 5, 6 and 7 are still further enlarged.

As shown, the thermophone comprises a casing made up of four segments, each lettered A. It will be understood, however, that the thermophone may be composed of any convenient number of parts, the parts being made to form a casing or inclosure of suitable shape. Each segment A is made of insulating material and is provided with openings through it as at a together with

recesses b to receive the strips B which carry the thermic loops. Each segment also has one or more peripheral slots a¹ to receive the wires by which the strips B may be connected in circuit. C, C¹ are caps suitably shaped to fit over and hold the segments A together in their appropriate form, the cap C¹ having an opening c through which the compressional air or heat waves escape to the ear in the ordinary use of the device. 60

In application for U. S. Letters Patent Serial No. 349,106, filed January 2, 1920, there is shown a machine for making thermic elements of a kind which may be used in this thermophone. Such elements comprise two 70 metallic strips B which are connected by loops D of Wollaston wire. As shown in Fig. 5, it will be noted that a small portion of the coating of the wire has been etched off as at d, these portions being the hot portion of the element. The strips B are, as shown, set into the recesses b which run the length of each segment, and thereafter the segment is used as a holder to hold the elements while they are being dipped for etching and also in the thermophone. 75

In making up the thermophone the segments carrying the strips B and loops D, whatever their number, are brought together, for example, as shown in Fig. 2, 85 so that they abut against each other and bring the loops of the elements in close proximity, though without touching. The cap C is placed over one end of the structure thus made and the cap C¹ is placed over the other end. It will be noticed from Fig. 1 that wires a² extend from the strips B to the caps C, C¹ through suitable openings in the segments. See Fig. 5 where the wires a² pass down through the openings a and then 90 through the grooves a¹ to their objective. 95

As I do not mean to limit myself to any particular connection of the elements with the circuit, I do not mean to specify exactly how these wires run, because anyone skilled in the art will see that the elements carried by the four segments may be connected in a variety of ways, for example, either in series, or parallel, or series parallel. So this particular type of apparatus lends itself to 100 various ways of using a current. 105

As I have said above, I prefer for simplicity and compactness of construction to use four insulating segments which fit together to form a cylinder, but a greater or 110

less number of segments properly fitted together or otherwise to form either a cylinder of a polygon or any other convenient shape, may be used, my invention in this regard 5 lying not in the precise construction shown, but in the bringing and binding together of a number of segments of any convenient shape, each of which shall carry a plurality of thermic elements and which when combined 10 will bring these elements into very close relation with each other in a chamber of any shape suitable for the purpose for which the instrument is designed. The thermophone may be of any desired length, thus 15 enabling the number of thermic elements to be varied according to the circumstances of use and, because of the comparatively large number of loops which may be located in the small air space when arranged as above described, the etched portion of each Wollaston wire may be much shorter than heretofore 20 and the loops as a whole much stronger so that the device may receive quite hard usage without fracture. As described in the application above referred to units of considerable 25 length may be easily connected and cut into lengths corresponding to the length of the thermophone in which they are to be used. The purpose of the caps is to clamp 30 the segments together so that they will form an air chamber within which the desired thermic results may be secured and from which desired sounds may be received. Other means may be used for this purpose, 35 for I do not intend to limit myself to the precise construction shown, and the segments may be otherwise attached together.

What I claim as my invention is:—

1. The device above described comprising 40 segments arranged to form a chamber and thermic units, each segment carrying one or

more of said thermic units arranged parallel to each other and projecting therefrom into said chamber in a plane or planes crosswise of the length thereof, and means for connecting said units with a source of current. 45

2. The device above described comprising a chambered casing made of insulating material and heat units located in the chamber in said casing and supported by said casing and arranged radially in planes at right angles to the axis of said chamber. 50

3. The device above described comprising segments, said segments being arranged to form a chambered casing, and means comprising caps to hold said segments together, and close ends of the air space, one of said caps being perforated to form an outlet to said chamber in combination with Wollaston wire loops supported by said segments and 55 lying in planes at right angles to the length of said chamber. 60

4. The device above described comprising segments carrying thermic elements, said segments being arranged to form a chambered casing within the chamber of which said elements lie and said elements comprising partially etched Wollaston loops, the etched portions of said loops lying in close proximity to each other about the axis of 65 said chamber and in planes at substantially right angles to the said axis. 70

5. In a device of the kind described, a series of segments of insulating material, each segment carrying parallel strips of conducting material, Wollaston wires connecting said strips, and means for holding said segments together to inclose a chamber, said Wollaston wires lying in planes at right angles to the length of said chamber. 75

BUDD D. GRAY.
